No. 11,979

October 19, 1880

UNITED STATES PATENT OFFICE.

ALFRED J. MANNING, OF NEW YORK, N. Y., ASSIGNOR TO ANDREW DOUGHERTY, OF SAME PLACE, AND THE NEW YORK CONSOLIDATED CARD COMPANY.

DESIGN FOR PLAYING-CARDS.

SPECIFICATION forming part of Design No. 11,979, dated October 19, 1880.

Application filed July 28, 1880. Term of patent 14 years.

To all whom it may concern:

Be it known that I, ALFRED J. MANNING, of the city, county, and State of New York, have invented a new and useful Design for Playing-Cards, of which the following is the specification.

My invention relates to an improved design for playing-cards; and it consists in the emblem and ornamentation, as hereinafter described, and illustrated in the drawing.

In the center of the card is the emblem A, constituting the ace of spades, the outline B of which is plain and unbroken except at its lower portion or stem, C, which is of swallow-tail form. Within the outline of the emblem is a bunch or spray of three leaves, D, the stems of which are joined by a clasp or holder, E, of any desired configuration. The stem of the center leaf of the bunch extends through the holder and into the stem of the emblem A, terminating in a bifurcated end, a. Within the outline of the spade is an ornamental border-line, b, and adjacent dots b', which follow the curvature of the outline. At the ends of the side lines of the emblem A, and just above the stem on both sides, this ornamental border-line b branches upwardly and laterally, forming graceful curves b² b² within the body of the emblem. Surrounding the emblem A is the border f of the panel F, the latter being ornamented with line-shading e. At the top of the panel F, and projecting considerably above the same, is a shell or fan-like ornament, x, having a leaf, x', projecting from each side of its base. Upon each side of the panel is a foliated ornament, H, which extends laterally

beyond the border f of the panel. Between the two extremities of the stem of the emblem is a foliated ornament, g.

The base of the design is a scroll, I. Above 40 the center fold of the scroll are arranged two curved arms, i i, which connect the scroll I with the main portion of the design. Immediately below the center of the top fold, g', of the scroll, and between the side folds, g² and g³, 45 thereof, is a bell-shaped ornament, g⁴.

I claim—

1. In a design for an ace of spades, the emblem A, ornamented with the lines B b b', the swallow-tail stem C, and the leaves D, substantially as shown.

2. A design for an ace of spades, consisting of the emblem A, ornamented with the lines B b b' and the leaves D, all within a shaded panel, F, the latter being provided with the 55 ornamental border f and the foliated ornaments H and shell x, substantially as shown.

3. A design for an ace of spades consisting of the combination of the emblem A, ornamented as described, the shaded panel F, having an ornamental border, f, and the foliated ornaments H and shell x, and the scroll-base I, provided with the foliated ornament g⁴, substantially as shown.

In testimony whereof I have signed my name 65 to this specification in the presence of two subscribing witnesses.

ALFRED J. MANNING.
